METAL EXTENSION SLIDE STRUCTURE

Frederick B. Walter, Wabash, Ind., assignor to
 B. Walter & Company, Wabash, Ind., a corpora-
 tion of Indiana

Application July 25, 1949, Serial No. 106,522

2 Claims. (Cl. 311—71)

1

The present invention relates to a metal slide structure, and finds its primary utility in connection with the separable elements of an extension table structure, though certain embodiments of the invention are also adaptable to use in drawer slides and other similar assemblies. The primary object of the invention is to provide a novel extension slide mechanism, the major elements of which lend themselves to construction from sheet metal. A further object of the invention is to provide a structure of the character described in which, very inexpensively, maximum relative movement of the rails is provided, while retaining structural rigidity among the elements. A further object of the invention is to provide a structure of the character under consideration in which the individual elements, made from sheet metal, may be unusually inexpensive in manufacture, and whereby the elements may be assembled in an unusually inexpensive fashion. A further object of the invention is to provide novel means for guarding against sagging in an extension table structure. Further objects of the invention will appear as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a plan view of an extension table embodying two slide structures constructed in accordance with my invention;

Fig. 2 is a transverse section taken substantially on the line 2, 2 of Fig. 1;

Fig. 3 is a plan view of an extension slide structure constructed in accordance with my invention, shown in collapsed condition;

Fig. 4 is a perspective view of one rail, showing the sliding shoe assembled therewith;

Fig. 5 is a perspective view of a companion rail adapted to be assembled with the rail of Fig. 4;

Fig. 6 is an enlarged end elevational view of the assembly of Fig. 3;

Fig. 7 is an enlarged perspective of a shoe forming an element of the present invention;

Fig. 8 is a side elevation of the rails of Figs. 4 and 5 in assembled and fully collapsed relation;

Fig. 9 is a similar view, the rail of Fig. 5 having been moved somewhat in an extending direction;

Fig. 10 is a similar view after the rail of Fig. 5 has been further moved in the same direction;

Fig. 11 is a similar view showing the parts in fully extended condition; and

2

Fig. 12 is a similar view showing the rail of Fig. 5 after it has been started toward collapsed position.

Referring more particularly to the drawing, it will be seen that I have illustrated a table comprising separable sections 20 and 21 connected and guided by extension slide structures indicated generally by the reference numerals 22 and 23. The structure 22 comprises a central or intermediate rail 24 which, in some assemblies, will be fixed to a central table frame structure (not shown), a supplementary rail 25 fixed to the table section 20, and a supplementary rail 26 fixed to the table section 21. The assembly 23 comprises elements 24', 25' and 26' entirely analogous to the elements 24, 25 and 26, respectively.

Since the assemblies 22 and 23 are identical, only one of them has been illustrated, and will be described, in detail.

20 The intermediate rail 24, illustrated in detail in Fig. 4, is formed to provide oppositely opening channels of generally C cross section. I have found that such a member may advantageously be made in the particular manner herein illustrated; the built-up structure being substantially less expensive than any unit of corresponding shape, produced in any other fashion known.

25 Thus, the rail 24 comprises a sheet metal channel member 27 including a web 28 and lateral flanges 29 and 30 projecting in a common direction from the lateral edges of the web. A similar channel member 31 comprises a web 32 and similar lateral flanges 33 and 34. The two channels 27 and 31 are assembled in back-to-back relation, their webs 28 and 32 being in abutment, and their flanges extending oppositely from the common plane of abutment, the flanges 29 and 34 being located in a common plane and the flanges 30 and 33 being located in a common plane. If desired, the webs 28 and 32 may be spot welded together; though I do not consider such spot welding to be necessary.

30 A sheet metal channel 35 comprises a web 36 and lateral flanges 37 and 38. The channel 35 is assembled with the channels 27 and 31 with its web 36 in abutment with the flanges 29 and 34 and with its flanges 37 and 38 overlying and engaging the free edges of the flanges 29 and 34, respectively. A channel 39 similar to the channel 35 is similarly associated with the flanges 30 and 33, its web 40 abutting the external surfaces of said flanges, and its flanges 41 and 42 overlying and engaging the free edges of the flanges 30 and 33. The webs 36 and 40 will preferably be secured to the flanges 29 and 34 and the flanges 30 and 33, respectively, by spot welding as at 43.

Thus, from sheet metal channels, there is constructed a rail formed to provide a central web, made up of the webs 28 and 32, having lateral flanges projecting in opposite directions from each lateral edge of the web, and made up of the flanges 29, 30, 33 and 34 and of the webs 36 and 40, each such flange terminating in a lip 37, 38, 41 or 42 projecting toward its companion lip and disposed in a common plane therewith.

The rail 26 comprises a sheet metal channel 44 including a web 45 and lateral flanges 46 and 47 projecting in a common direction from the lateral edges thereof. A sheet metal channel 48 has its web 49 disposed in abutment with the flange 46, one flange 50 of the channel 48 being, throughout at least a portion of its length, in abutment with the web 45, and the other flange 51 of the channel 48 overlying and engaging the free edge of the flange 46. A further sheet metal channel 52 is similarly associated with the flange 47, its web 53 abutting said flange, its flange 54 abutting the web 45, and its flange 55 overlying and engaging the free edge of the flange 47. The channels 48 and 52 will be suitably secured in position; as by spot welding, to the flanges 46 and 47 or to the web 45, or both; and it will be seen that the integrated structure provides a web having lateral flanges projecting in a common direction, and lips projecting from the free edges of said flanges toward each other, and disposed in a common plane. Preferably, the element 48 will be formed with a portion 56 providing projections, substantially in the plane of the web 49, having perforations 57 therein for the accommodation of fastening means whereby the rail 26 may be secured to, for instance, the table top section 21.

The rail 25 is substantially similar to the rail 26, comprising a sheet metal channel 58 formed to provide a web 59 and lateral flanges 60 and 61. A sheet metal channel 62 has its web 63 abutting the flange 60, its flange 64 abutting the web 59, and its flange 65 overlying and engaging the free edge of the flange 60. The channel 62 will be provided with a portion 66 formed with perforations 67, these parts being similar to the portions 56 and 57 of the channel 48. A channel 68 is similarly assembled with the flange 61, its web 69 abutting said flange, its flange 70 abutting the web 59, and its flange 71 overlying and engaging the free edge of the flange 61. The channels 62 and 68 will be suitably secured to the flanges 60 and 61, respectively, as by spot welding.

Two shoes 72 and 73 are slidably mounted in the channel defined by the web 28, flanges 29 and 30, and lips 37 and 41; and two shoes are similarly slidably received in the channel defined by the web 32, flanges 33 and 34, and lips 38 and 42, only one of said last-mentioned shoes, 74, being illustrated in Fig. 6. The four shoes are identical in construction, and therefore only one has been illustrated in detail in Fig. 7. Each shoe comprises a body portion 75 of sheet metal having lateral bridge portions 76 turned from the plane of the body in a common direction to support opposite wings 77 and 78 disposed in a common plane offset from the plane of the body portion 75. The wing 77 is provided at its opposite ends with extensions 79 and 80 adapted, when the bridge pieces 76 are located between the termini of the lips 37 and 41, to project toward the flanges 29 and 30 and to engage those surfaces of the lips 37 and 41 which face the web 28. The wing 78 is provided with

similar extensions 81 and 82 which are similarly engaged with those lips. The body portion 75 is provided at its opposite ends with extensions 83 and 84 adapted to engage the surfaces of the lips 51 and 55 which face the web 45; and it will be obvious that, when the parts are so assembled, the projections 79, 80, 81, 82, 83 and 84 cooperate with the lips 37, 41, 51 and 55 to prevent separation of the rails 24 and 26 in a direction perpendicular to the webs 28 and 45; while the bodies of the shoes prevent separation of said rails in a direction perpendicular to the flanges 29 and 30. Relative movement between the shoes and the cooperating rails (and therefore between the rails themselves) in the direction of length of the rails, however, is unimpeded by the structure thus far described.

As is clearly to be seen in Fig. 7, the degree of projection of the extensions 79 and 81 above the upper edges of the bridge pieces 76 somewhat exceeds the degree of projection of the extension 83; and the degree of projection of the extension 84 below the lower edges of said bridge pieces similarly exceeds the degree of projection of the extensions 80 and 82. Consequently, when the parts are assembled, the surfaces 49 and 63 of the members 26 and 25 are disposed substantially in a common plane somewhat below the plane of the surface 36 of the member 24.

As will be apparent from Fig. 1, the table sections 20 and 21 are supported primarily at their remote ends; and no intermediate floor-supported element is provided. A tendency therefore exists for the units 22 and 23 to sag at their middles when the table sections are separated; and the means described in the preceding paragraph is provided to compensate for that tendency in the manner clearly illustrated in Fig. 6. Similar compensation is effected, of course, in a unit consisting solely of counterparts of the elements 25 and 26 directly joined by shoes 72 and 73.

An ear 85 is turned from the lateral extremity of each wing 77 and 78, in the direction of the web 28, and the body 75 is formed to provide an integral projection, which may take the form of the extrusion indicated at 86, extending in the direction of the web 45. A stop element 87, fixed with respect to the web 28, and a second stop element 88, similarly fixed and longitudinally spaced from the element 87, cooperate with the ears 85 to limit the degree of movement of the shoe 72 relative to the rail 24. A stop element 89 and a stop element 90, fixedly longitudinally spaced upon the web 45 and projecting therefrom into the path of the extrusion 86, cooperate to limit the degree of relative movement between the shoe 72 and the rail 26. As shown, the elements 87 and 89 are pins, while the elements 88 and 90 are extrusions; but it will be understood that any suitable form of stop element, capable of performing the confining function, may be used.

Similarly, the shoe 73 is confined between stop elements 91 and 92 fixed with respect to the rail 24, and between stop elements 93 and 94 fixed with respect to the rail 26.

It will be seen that the stopping arrangement maintains a longitudinal spacing (varying in degree) at all times between the shoes 72 and 73, so that the rails 24 and 26 are suitably braced against relative separation; and it will further be seen that, because the shoes are longitudinally movable relative to both of the rails, a substantially greater degree of longitudinal relative

movement between the rails is possible than could occur if the shoes were fixed relative to either of the rails. It will be apparent that the shoe 74 and its mate, through which the rail 25 is assembled with the rail 24, are similarly cooperative with said rails 24 and 25.

In Fig. 8, I have shown the rail 26 fully retracted with respect to the rail 24; viz., in the position of Fig. 3. In this position, the extrusion 90 is engaged with the extrusion 86 of the shoe 72, while the ear 85 of the wing 78 is engaged with the stop pin 87. Thus, the rail 26 is held against movement to the right relative to the shoe 72, and the shoe 72 is held against movement to the right relative to the rail 24. The shoe 73 is engaged by the pin 97, but is not engaged by any element fixed with respect to the rail 24.

If, now, the rail 26 is moved toward the left to the position of Fig. 9, the extrusion 90 will leave the shoe 72, the rail 26 sliding with respect to the shoe 72 and probably not causing any movement of said shoe. The pin 94 will leave the shoe 73, which shoe probably will remain stationary with respect to the rail 24, and the extrusion 93 will be moved toward engagement with the extrusion 86 of the shoe 73.

Further movement of the rail 26 to the position of Fig. 10 will carry with it the shoe 73, through engagement between the extrusions 93 and 86; and, at the position of Fig. 10, the pin 89 will engage the extrusion 86 of the shoe 72.

As the rail 26 continues to move to its fully extended position, illustrated in Fig. 11, the extrusion 93 will carry the shoe 73 until the ear 85 of the wing 78 engages the pin 91, while the pin 89 carries the shoe 72 until the ear 85 of its wing 78 engages the extrusion 86. At this point, the rail 26 is, of course, retained against any further movement toward the left.

As the rail 26 is moved toward the right from the position of Fig. 11, the pin 89 will leave the shoe 72 and the extrusion 93 will leave the shoe 73, the rail 26 moving without affecting the shoes until the pin 94 engages the extrusion 86 of the shoe 73, at the position of Fig. 12, to begin to move said shoe away from the pin 91. Some time thereafter, the extrusion 90 will engage the extrusion 86 of the shoe 72, whereafter said shoe 72 will be carried with the rail 26 until its ear 85 of its wing 78 engages the pin 87 to stop further movement of the rail 26 with the parts in the positions of Fig. 8.

I claim as my invention:

1. Metal slide structure including a first rail comprising a web, flanges projecting in a common direction from the lateral edges of said web, lips projecting toward each other from the extremities of said flanges substantially in a common plane parallel with said web and spaced therefrom in said one direction, other flanges projecting in the opposite direction from the lateral edges of said web, and other lips projecting toward each other from the extremities of said other flanges substantially in a common plane parallel with said web and spaced therefrom in said opposite direction, a second rail comprising a web, flanges projecting in a common direction from the lateral edges of said

second rail web, and lips projecting toward each other from the extremities of said second rail flanges, two shoes, each straddling said first-named lips and said lips of said second rail for longitudinal movement relative to both rails, stop means on both rails positioned in the paths of said shoes to limit such movement, a third rail comprising a web, flanges projecting in a common direction from the lateral edges of said third rail web, and lips projecting toward each other from the extremities of said third rail flanges, two further shoes, each straddling said other lips and said lips of said third rail for longitudinal movement relative to said first rail and said third rail, stop means on said first rail and on said third rail positioned in the paths of said further shoes to limit such movement, said first rail comprising a sheet metal channel having a web and lateral flanges and a second sheet metal channel having a web and lateral flanges, said channels being arranged with their webs in abutment and with their flanges projecting oppositely from the plane of abutment of such webs, a third sheet metal channel arranged with its web abutting one flange of each of said first and second channels and with its flanges overlying the free edges of said flanges of said first and second channels, and a fourth sheet metal channel arranged with its web abutting the other flange of each of said first and second channels and with its flanges overlying the free edges of said last-named flanges of said first and second channels.

2. The structure of claim 1 in which each of said second and third rails comprises a sheet metal channel having a web and lateral flanges and a further sheet metal channel for each such flange, each such further channel having a web abutting the outer surface of one flange of said first-named channel, a lateral flange abutting the web of said first-named channel, and a lateral flange overlying the free edge of said one flange of said first-named channel and projecting toward the other flange of said first-named channel.

FREDERICK B. WALTER.
